Patented Sept. 29, 1959

186,250

SEWING MACHINE BOBBIN

Stephen V. Bacco, Brooklyn, N.Y., assignor to Coats & Clark, Inc., New York, N.Y., a corporation of Delaware

Application November 10, 1958, Serial No. 53,315

Term of patent 14 years

(Cl. D70—2)

Fig. 1 is a top plan view of a sewing machine bobbin showing my new design;

Fig. 2 is a side elevational view; and

Fig. 3 is a section through 3—3 of Fig. 1.

I claim:

The ornamental design of a sewing machine bobbin, substantially as shown.
